UNITED STATES PATENT OFFICE.

JOHN SCHERNER AND EDWARD HUTCHENS, OF MILWAUKEE, WISCONSIN, ASSIGNEES
TO PIERCE WRAPPING MACHINE COMPANY, OF CHICAGO, ILLINOIS, A CORPOR-
ATION OF ILLINOIS.

WRAPPING-MACHINE.

1,387,016.

Specification of Letters Patent. Patented Aug. 9, 1921.

Application filed April 3, 1916. Serial No. 88,563.

To all whom it may concern:

Be it known that we, JOHN SCHERNER and EDWARD HUTCHENS, citizens of the United States, residing at Milwaukee, in the county 5 of Milwaukee, State of Wisconsin, have invented new and useful Improvements in Wrapping-Machines, of which the following is a specification.

The invention relates to wrappings and 10 wrapping machines.

It relates particularly to wrappings for automobile tires and the like and to machines for applying the wrapping.

Automobile tires, coils of wire, strips of 15 molding, finished metal rods and the like are often wrapped in paper or other fabric for the purposes of transportation. The wrapping fabric is usually cut in the form of strips which are spirally wound about the article to 20 completely cover it. It is difficult to wrap the strip spirally and cause it to conform to the shape of the article. Moreover, when one of the convolutions of a spirally wound wrapping strip is broken or damaged, as frequently happens, the wrapping tends to 25 unwind from the article leaving it uncovered. It is accordingly important that a fabric strip be devised which will readily conform to the shape of the article about which it is 30 to be wrapped and that means be provided for rapidly applying the fabric in a neat and efficient manner so that when one of the convolutions of the wrapping is broken the remainder of the wrapping will not be affected.

One of the objects of the present invention is to provide an improved fabric strip wrapping.

Another object is to provide an improved 40 machine for applying a fabric strip wrapping to an article.

Another object is to provide an improved machine for manipulating a fabric strip so that the same will conform to the shape of 45 the article about which the strip is to be wound.

Another object is to provide an improved machine for wrapping a fabric strip about an article and applying adhesive material to 50 said strip as it is being wound about the article.

Other objects and advantages of the invention will hereinafter appear.

The accompanying drawings illustrate an 55 embodiment of the invention.

The views of the drawings are as follows:

Figure 1 is a side elevation of a wrapping machine embodying the invention.

Fig. 2 is an end elevation of the machine.

Fig. 3 is a transverse section on the line 60 3—3 of Fig. 1.

Fig. 4 is a horizontal section on the line 4—4 of Fig. 2.

Fig. 5 is a sectional view of a portion of the shuttle of the machine showing the 65 mounting of the fabric strip and the means for manipulating the edges of the strip for causing the same to conform to the shape of the article.

Fig. 6 is a sectional view of a wrapped 70 tire.

Fig. 7 is an elevation of the tire wrapping showing the manner in which the edges thereof are crimped or creased.

Fig. 8 is a fragmentary detail of the 75 wrapper strip showing the edge crimped.

Fig. 9 is a transverse section of the crimped sheet.

The machine is provided with a frame 1 upon which is mounted a driving motor 2. 80 The driving shaft 3 has an annular gear 4 thereon which drives a transverse shaft 5 through a suitable train of gears 6 and 7 which reduce the revolutions of shaft 5 to the desired number.

The upper gear wheel 4 is keyed or otherwise secured to the motor shaft and the gear wheel 6 is mounted on a stub shaft 8 while the gear wheel 7 is loose on the transverse shaft 5 and is adapted to be locked to the 90

same by a clutch 9 of any desired construction having a member slidably interlocked with the shaft and movable into and out of engagement with the gear wheel 7. When the clutch is moved into engagement with 95 the gear wheel 7 the shaft 5 is connected with and is adapted to be driven by the motor 2. The transverse shaft which is located at the rear portion of the machine is journaled in suitable bearings of the supporting frame and it has fixed to it a roll 11

having a suitable friction lining, not shown, which is provided at opposite sides with flanges 12 and adapted to engage and rotate an annular shuttle 13. The transverse shaft 100 5 also carries a worm 14 which meshes with a worm wheel 15 keyed or otherwise secured to one of a pair of longitudinal shafts 16 and 17 which are simultaneously rotated in the same direction and which are connected 105

110

by sprocket gearing located at the rear end of the longitudinal shafts 16 and 17 and consisting of a sprocket chain 18 and sprocket wheels 19 fixed to the rear ends of the shafts 5 16 and 17 and receiving and meshing with the said sprocket chain 18.

The shuttle 13 which is constructed of aluminum or other suitable material is supported in position for rotary movement by 10 the rubber covered roller 11 and upper and lower front flanged rollers 20 and 21 which are mounted on suitable stub shafts located at one side of the machine, the other side being open. The annular shuttle is provided 15 with a hinged section 22 pivoted at 23 and constituting a door for enabling the annular shuttle to be readily placed around a tire, or other annular article, or to permit the tire 23^a or other article, to be readily placed 20 in and removed from the machine through the hinged section or door. The hinged section or door is locked in its closed position by a spring actuated pin or bolt 24 slidably mounted on the hinged section 22 at the free 25 end thereof and movable into and out of engagement with the adjacent end of the body portion of the shuttle and maintained normally in such engagement by a coiled spring 25. The latch is also equipped with 30 an operating lever 26 pivoted at an intermediate point and having one of its arms constituting a handle and its other arm connected with and adapted to move the pin or bolt 24 rearwardly against the action of the 35 spring 25 to open the hinged door or section 22. The hinged door or section when open enables the shuttle to be readily disengaged by the upper and lower flanged rollers and the rubber covered roller to permit the removal 40 of the shuttle for filling the same with glue or other adhesive material.

The interior of the shuttle 13 is hollow except for the gate 22. It forms a receptacle for liquid adhesive material such as 45 liquid glue or the like, a suitable filling opening 27 being provided which is normally closed by a plug or stop. As the shuttle rotates the adhesive material is thrown outwardly by centrifugal force and caused to 50 pass through an opening and be applied to the fabric strip in a manner hereinafter described. The shuttle, as shown in Fig. 1, rotates in a clockwise direction and the opening through which the adhesive material 55 passes to be applied to the strip is located at the rear end of the hollow interior of the receptacle so that the rotation of the shuttle tends to cause the adhesive material to collect at the end of the shuttle in which the 60 opening is located.

The tire or other article is supported and fed to the wrapping mechanism hereinafter described by the front portions of the longitudinal shafts 16 and 17 which are journaled 65 in suitable bearings of the supporting frame

of the machine. The front portions 28 and 29 are reduced and the tire or other article is supported and fed by such reduced portions. The reduced portion 28 is located in advance of the strip or ribbon 30 of wrapping material and in wrapping a tire the tire is engaged at the bead by opposite squeezing rollers 31 and 32 set at an angle or inclination and adapted to engage and interlock with the tire at the base portion thereof 70 for maintaining the tire in a compact condition while the tire is being wrapped. The rear squeezing roller 31 is permanently mounted on one of the bearings of the longitudinal shaft 16 and the other roller 32 is 75 mounted on a pivot 33 which is carried by a slidable sleeve 34 preferably mounted on the shaft 16 at the reduced portion thereof and maintained in engagement with the tire by a coiled spring 35 interposed between and 80 whose ends are engaged in the sleeve and the front bearing 36 of the reduced portion 28 and the sleeve 34 for urging the front or outer squeezing roller inwardly or rearwardly. By this means the squeezing roller 85 32 is maintained in engagement with the tire and is also held against rotary movement on the reduced portion 28 of the shaft 16.

The fabric strip which may be paper, cloth or any other suitable material, is carried by 90 a spool 36 that is arranged on a rotary spool holder 37 mounted on a horizontal stud or spindle 38 and preferably consisting of a sleeve and an inner plate or flange 39 which is interposed between the spool and the adjacent portion of the shuttle of the machine. The inner end 40 of the spindle is threaded and tapped into the rotary shuttle. The spool is retained on the spool holder by a removable collar 41 and a locking washer 42 100 105 but any other suitable device may of course be employed as will be readily understood.

The ribbon of wrapping material is led from the spool over a horizontal feed tube 43 constituting a guide for the wrapping material and provided at its outer end with a head or flange 44 and having its inner end 45 threaded and tapped into the rotary shuttle. The inner portion of the tubular guide 43 is provided with an outlet perforation 46 110 and the paper or cloth ribbon or strip is held against the perforation or discharge orifice by a spring 47 which is also adapted to constitute a closure or valve for the discharge orifice in event of breakage of the wrapping 115 ribbon so that the glue or other adhesive material will not leak or waste.

The diameter of the feed tube 43 is reduced gradually for a part of its length near the outer end, being smallest at the base of the collar 44. A roller 70 conforming to the shape of the reduced portion is rotatably mounted on the shaft 71 and is held yieldably against said reduced portion and with 125 axis in the same vertical plane by the spring 130

72. As the tape 80 is fed to the article or tire to be wrapped the roller 70 coating with said reduced portion provides a continuous series of crimps or accordion plaits 81, which, 5 as the strip is applied to the article, are adapted to automatically fold or adjust themselves to cause the strips winding on the articles flat and prevents buckling of the strip or other deformations in the wrapping as it is applied and after application 10 thereof.

When the clutch is thrown into operation the shuttle is caused to revolve and the tire or other article is fed to the same at right angles thereto and the paper thus traveling around the tire or other article wraps the same spirally as it unwinds from the roll. As the edge of the paper or other wrapping material travels over the discharge aperture, 20 centrifugal force acting on the glue or other adhesive material in the shuttle throws the glue against the edge of the paper and the ribbon of wrapping material is cemented or glued where it overlaps the layer beneath it. 25 The bands of the wrapper are thus cemented or glued together making practically a one piece wrapper.

In order to enable the glue or other adhesive material to flow freely through the discharge aperture under the influence of centrifugal force the shuttle is provided with a vent aperture 48 which is closed by a needle valve 49 when the shuttle is stationary. The needle valve which is in the form of a substantially L-shaped lever is pivoted intermediate of its ends at 50 in a suitable bracket or support and its front portion is provided with the valve proper while its rear portion is equipped with a weight 52 30 adapted when the shuttle revolves to move outwardly through centrifugal force and open the valve and permit air to enter the shuttle through the vent opening. As soon as the shuttle stops the valve is automatically closed by a spring 53 which is secured at one end to the weight and has its other end bearing against the shuttle as clearly shown in Fig. 1 of the drawings. The weight is adjustable on the lever to secure the desired action of the spring and the weight. A cord or wire 54 is fed under the wrapper from an overhead spool 55 journaled in suitable bearings on standards 56 40 of the supporting frame but any other suitable supporting means may of course be employed for mounting the spool of twine, wire or cord. The cord, wire or twine is bent downwardly from the spool and passes over a guide pulley 57 and is fed to the tire or other article preferably centrally of the tread as illustrated in Fig. 1 of the drawings. The cord is interposed between the tire or other article and the wrapper and is adapted to be pulled to cut the wrapper and

remove the same from the tire or other article. When the clutch is thrown out of operation by the means hereinafter described the shuttle is engaged by the brake lever 58, fulcrumed at one end at 59 and provided with an engaging portion or shoe 60 and 70 having a rearwardly extending arm which is connected by a rod or link 61 with an arm 62 of a rock shaft 63 having a treadle 64 mounted on it and also provided with an arm 65 which is connected by a link or rod 75 67 with a clutch shifting lever 68. The lever 68 is fulcrumed intermediate of its ends at 69 and its upper end is connected with the clutch. When the clutch is thrown into engagement the brake lever is moved 80 out of engagement with the shuttle and when the clutch is moved out of its engaging position the brake is applied to the shuttle to stop the latter.

It is to be understood that the structure 85 shown is for purposes of illustration only, and that many other structures may be devised which embody the invention and which come within the spirit and scope of the appended claims.

What we claim is:

1. A wrapping machine comprising a rotating shuttle, means secured thereto for carrying a wrapping strip and mechanism secured to the shuttle for crimping a sheet 95 as it is being applied to the article wrapped.

2. A wrapping machine comprising rotatable supporting members, a rotatable shuttle, means secured thereto for carrying a wrapping strip and mechanism for making 100 crimps or plaits in the strip along one edge thereof.

3. A wrapping machine comprising rotatable supporting members, a rotatable shuttle, means secured thereto for carrying a 105 wrapping strip, mechanism for making crimps or plaits in the strip along one edge thereof and mechanism for applying an adhesive liquid along the edge of the strip oppositely from the crimps.

4. A machine for wrapping articles comprising means for winding a strip of fabric about the article, means for applying an adhesive to said strip as it is being wound to unite the convolutions of the winding and means for simultaneously crimping the sheet 115 along one edge thereof.

5. A machine for wrapping annular articles comprising means for winding a strip of fabric about the article in overlapping layers, and means for applying an adhesive liquid to said strip to unite the overlapping edges of the winding, and means for yieldingly holding the strip on said means adapted to act as a valve to prevent escape of the 125 adhesive liquid on removal of the strip.

6. A machine for wrapping annular articles comprising a shuttle having a reservoir

- for containing an adhesive liquid, a valve controlled member for applying the liquid to a strip of wrapping material and a check valve acting automatically to admit air into the reservoir when the shuttle rotates and to prevent escape of adhesive liquid when the shuttle is at rest.
7. A machine for wrapping annular articles comprising means for winding a strip 10 of fabric about the article, means for plaiting one edge of said strip to cause it to conform to the shape of said article, and means for applying an adhesive to said strip as it is being wound to unite the convolution 15 of the winding.
8. A machine for wrapping annular articles comprising means rotating through the opening in the annular articles for winding a strip of fabric about the article, and 20 means for crimping one of the edges of said strip to cause said strip to conform to the shape of the article.
9. A machine for wrapping annular articles comprising means for winding a strip 25 of fabric about the article, said strip passing through the central opening of the annular article, means for crimping one of the edges of said strip to cause said strip to conform to the shape of said article, and 30 means for applying an adhesive to said strip as it is being wound to unite the convolutions of the winding.
10. A machine for wrapping annular articles comprising means rotating through 35 the opening in the annular article for winding a strip of fabric about the article, and means for producing plaits or crimps in one edge of said strip to cause said strip to conform to the shape of said article.
- 40 11. In a wrapping machine a revoluble shuttle, means for rotating through the shuttle an article to be wrapped, means for applying a wrapping strip to the article and mechanisms rotatable with the shuttle adapted to simultaneously apply an adhesive material to one edge of the wrapping strip and to form plaits and crimps along the opposite edge of the wrapping strip.
12. In a wrapping machine means for supporting and rotating an article to be wrapped, a rotatable hollow shuttle adapted to contain an adhesive liquid, a valve controlled outlet for said shuttle over which the wrapping strip passes and an automatically 55 operating vent valve operated by rotation and stoppage of the shuttle.
13. In a wrapping machine means for supporting and rotating an article to be wrapped, a rotatable hollow shuttle adapted 60 to contain an adhesive liquid, a valve controlled outlet for said shuttle over which the wrapping strip passes, an automatically operating vent valve operated by rotation and stoppage of the shuttle and a plaiting 65 mechanism carried by the shuttle to form plaits in the strip as the adhesive material is applied.
14. A machine for wrapping articles comprising means for winding a strip of fabric around the article, said means including a shuttle having a receptacle for containing adhesive material, said receptacle having an outlet over which the fabric passes whereby the adhesive is applied to the fabric as it passes over the outlet and is wound on the 75 article, and yielding means for holding the fabric strip against the outlet, said means also constituting a valve for closing the outlet.
15. A machine for wrapping articles comprising means for winding a strip of fabric around the article and for applying adhesive material to the strip, said means including a rotary shuttle having a hollow interior for the reception of adhesive material and provided with a hollow laterally projecting guide over which the strip is adapted to pass and which is provided with an opening so that the adhesive material is applied to the fabric as it passes over the 85 guide, said shuttle having a vent therein to permit uniform flow of adhesive material and a valve adapted to be opened by centrifugal force when the shuttle is rotating and to automatically close when the shuttle 90 is at rest.
16. A machine for wrapping annular articles comprising means for winding a strip of fabric about the article, means for producing a series of folds or creases in one 95 edge of the fabric to cause it to conform to the shape of the article, said last named means comprising a guide over which the strip passes and from which it is led to the article at an angle, said guide having a recess at one side thereof and being provided with means for forcing one edge of the strip into said recess to produce folds or 100 creases in said edge.
17. In a wrapping machine an annular 110 shuttle having its center clear to permit the rotation of a tire-casing therethrough, means to support and rotate a tire casing through the plane of said shuttle, a source of wrapping material mounted on said shuttle; said 115 shuttle being adapted to wind said material about said casing spirally, and a device mounted on said shuttle adapted to produce a moistened adhesive condition of said wrapping material whereby the successive 120 spiral convolutions of the wrapping material will be adhesively joined to one another.
- In witness whereof, we have hereunto subscribed our names in the presence of a 125 witness.
